(57) **CLAIM**

The ornamental design for video borescope housing, as shown and described.

DESCRIPTION

FIG. 1 is an isometric view of a video borescope housing for holding a display screen;

FIG. 2 is a front view of the video borescope housing of FIG. 1;

FIG. 3 is a rear view of the video borescope housing of FIG. 1;

FIG. 4 is a left view of the video borescope housing of FIG. 1;

FIG. 5 is a right view of the video borescope housing of FIG. 1; and,

FIG. 6 is a top view of the video borescope housing of FIG. 1.

Where applicable, elements are shown in broken lines herein for illustrative purposes only, and form no part of the claimed design.

1 Claim, 6 Drawing Sheets**FIG. 1**

FIG. 2

FIG. 3

FIG. 4

FIG. 5

FIG. 6
